DRESSING MECHANISM

Robert S. Condon and Clarence T. Galloway,
Rochester, N. Y., assignors to Gleason Works,
Rochester, N. Y., a corporation of New York

Application October 27, 1932, Serial No. 639,800

18 Claims. (Cl. 125—11)

The present invention relates to dressing mechanisms such as employed in truing the operating surfaces of grinding wheels and in particular it relates to manually-controlled dressing mechanisms.

Few grinding machines are provided with automatic dressing mechanisms. The common practice is for the operator to dress the grinding wheel by hand by manually reciprocating a truing tool across the surface to be dressed. Now, a reciprocating truing tool turns a continuous helix on the surface of a grinding wheel and the smoothness of the surface ground by the wheel depends directly on how fine and how uniform is the lead of this helix. In hand-operated dressing mechanisms, as heretofore built, the human element has always entered too much into the dressing operation and it has been extremely difficult to get satisfactory results especially where precision grinding was desired. At one time, an operator would move the truing tool across the grinding wheel faster than at another time and no operator's nerves were ever so steady that he moved the truing tool across the whole face of the wheel at an absolutely uniform speed.

Another objection to hand-dressing mechanisms of previous constructions has been the loss of time of the operator in the dressing operation. The operator has had to manipulate the tool to effect the dressing operation and, therefore, the time required for dressing has meant time that could not be devoted to other work.

The primary purpose of the present invention is to provide a manually-controlled dressing mechanism in which the human element is entirely eliminated as a factor in the dressing operation.

A further object of the invention is to provide a dressing mechanism in which the fineness of dressing can be predetermined and is not dependent on the skill of the operator.

Another object of the invention is to provide a dressing mechanism which is fully protected from water and grit and which will, therefore, operate an extended period without attention. In this connection, it is a further purpose of the invention to incorporate into a dressing mechanism, means for sending a blast of air through the relatively movable parts, each time the dressing mechanism is operated, thereby blowing grit and dirt out from between the parts.

Another object of the invention is to provide a dressing mechanism which will be extremely compact and which will occupy a minimum of space so that it can be readily used on existing machines.

without interference with the operation of such machines.

Another object of the invention is to provide a dressing mechanism which an operator may put into operation simply by movement of an operating handle and which will then complete the dressing cycle without further attention from the operator.

Still another object of the invention is to provide a fluid-pressure operated dressing mechanism in which a pair of dressers can be so coupled together that a single control valve can be employed to control the operation of both.

A further object of the invention is to provide a dressing mechanism in which the dressers for truing a side and the tip surface of a grinding wheel are carried on the same part and operated through a single mechanism and by a single movement, thus eliminating one of the dressing units heretofore required for dressing the surfaces of a grinding wheel and reducing the cost of a complete dressing unit and rendering the unit more compact.

The dressing mechanism of the present invention differs from previous dressing mechanisms in that, while manually controlled, it is actually operated automatically. The movement of the truing tool across the face of the wheel takes place under hydraulic power. The human element is entirely eliminated and a smooth and uniform movement of the truing tool across the grinding wheel is insured without the cost and complication of an automatic dressing mechanism. A manually shiftable reversing valve controls the reciprocation of the truing tool or tools across the side or sides of the grinding wheel while the desired rate of travel of the truing tool or tools across the wheel is controlled by a manually adjustable throttle valve. The rate of movement of the truing tool or tools across the grinding wheel can be predetermined exactly by adjustment of the throttle valve and is entirely independent of the skill of the operator.

The reversing valve is a sliding valve and is shifted by movement of an operating handle or knob secured thereto. Through an ingenious arrangement the throttle valve can be adjusted by rotating this same knob or handle.

The truing tool is secured to the head of a piston rod that is hydraulically reciprocated under control of the reverse and throttle valves. To obtain compactness together with strength and rigidity, the piston rod is mounted to reciprocate in an eccentric bore provided in a relatively fixed guide member or support and the truing tool is

guided in its reciprocation by a key that engages in a longitudinal slot cut into the guide member or support at its thickest part, that is, cut into the periphery of the guide-member at the point most remote from the center of its bore. The key is carried by a skirt or sleeve that is connected to the head of the piston rod and that surrounds the guide member.

Telescoping guards are provided to prevent entry of water or grit into the parts as the truing tool reciprocates back and forth. As a further means of protection, the device already referred to is provided for blowing out the guards automatically each time the dressing mechanism is operated. There is a valve mounted in the relatively fixed guide or support. This valve is so constructed that when the truing tool moves outwardly across the grinding wheel, air is drawn in between the skirt of the piston rod head, and the rod or support, and, when the truing tool makes its return stroke, the valve is substantially closed and this entrapped air is forced out between the parts of the telescoping guards, blowing grit and water out.

In one embodiment of the invention, as mentioned above, the operator is only required to push the reverse valve in to start the truing operation and the rest of the operation will be completed without his further attention. When the reverse valve is pushed in, hydraulic pressure is applied to one side of the piston to which the truing tool is connected and the truing tool is moved across the face of the grinding wheel. The exhaust fluid from the other side of the piston operates a hydraulic load and fire mechanism. When the truing tool has traveled across the face of the grinding wheel, this load and fire mechanism is tripped and the reverse valve is reversed. This causes the truing tool to be returned to original position clear of the wheel and the truing operation is thus completed. When this embodiment of the invention is used, it takes but a second for the operator to start the truing mechanism and he is left free to attend to the grinding machine or to take care of other duties in connection with his work.

By suitably proportioning the parts, it is possible, through use of the load and fire mechanism, to secure a dwell at the end of the stroke of the member carrying the truing tool. The purpose of providing this dwell is to allow a tip truing tool to be mounted on the same reciprocable part as one of the side truing tools. Thus, the tip truing tool is brought into engagement with the tip surface of the grinding wheel at the end of the forward stroke of the side truing tool and the dwell in the stroke of the reciprocable part allows the tip truing tool to remain in engagement with the grinding wheel long enough to true up the tip surface of the grinding wheel. As against previous constructions, this improvement eliminates one truing unit entirely, namely, the tip truing unit, with the resultant important gain in compactness. Space is always a vital factor within a grinding machine.

The principal features of the invention have been referred to above. The invention includes, however, several further constructional improvements that will be apparent hereinafter from the specification and from the recital of the appended claims.

In the drawings:

Figure 1 is a view illustrating somewhat diagrammatically one embodiment of the present invention and showing in section the reverse valve

and the dressing unit and further illustrating in dotted lines how a second dressing unit might be coupled into the system so that two units for dressing opposite sides of a grinding wheel can be controlled simultaneously from a single reversing valve;

Figure 2 is a view showing another embodiment of the present invention in which means are incorporated enabling the dressing mechanism to complete its cycle automatically once the reversing valve is tripped. In this figure two dressing units are shown coupled together and in position for dressing opposite sides of a grinding wheel, and one of the units includes both a side and a tip truing tool. Further, this figure shows an arrangement wherein the side truing tools move simultaneously in opposite directions;

Figure 3 is a diagrammatic view on a reduced scale showing how the reversing valve and dressing units may be connected to have the two side truing tools moving simultaneously in the same direction;

Figure 4 is a transverse sectional view through one of the dressing units, taken at a point such as indicated by the line 4-4 in Figure 1;

Figure 5 is a fragmentary sectional view on the line 5-5 of Figure 4;

Figure 6 is an enlarged fragmentary view showing the breather valve which controls admission of air between the reciprocating parts during operation of a dresser unit;

Figure 7 is a fragmentary plan view, showing the cylinder-end of one of the dresser units; and

Figure 8 is an end view of the trip-lever, which operatively connects the load and fire mechanism with the reverse valve.

In the drawings, I have shown several different embodiments of my invention. The same dressing unit can be employed in all the various embodiments of my invention. If it is required to dress two sides of a grinding wheel, the dressing unit employed for dressing one side of the wheel can be duplicated. This is true regardless of whether the two dressing units be arranged to move simultaneously in opposite directions or simultaneously in the same direction.

Referring then to the drawings by numerals of reference, 10 indicates a support or guide constituting a relatively fixed part of a dressing unit constructed according to the present invention. The support 10 is formed to provide a cylinder 11 and a cylindrical extension or guide 12. The extension or guide 12 is bored eccentrically of its periphery, as clearly shown in Figure 4.

A piston 14 is mounted to reciprocate in the cylinder 11 and to the piston 14 there is secured by a nut 16 a piston-rod 15. The piston-rod projects forwardly through one end-wall of the cylinder 11 into and through the eccentric bore of the guide-extension 12. The piston-rod is of a diameter to fit snugly the bore of the guide-extension so that the part 12 serves as a bearing and support for the piston-rod in its movement.

The piston-rod 15 is formed with an enlarged head at its outer or forward end and to this head there is secured a sleeve or skirt 18. The skirt is held in position by a nut 17 which threads onto a stud 19 that is integral with the piston-rod 15. The sleeve or skirt 18 is tubular in shape and fits over and telescopes on the guide-extension 12.

There is a peripheral groove 20 cut longitudinally in the guide-extension 12 at the thickest portion of the same, as shown in Figure 4. There is a key 21 secured by screws 22 to the skirt 18. This key engages in the groove 20. A longitudinally ta-

pering gib 23 is also mounted in the groove 20 and can be adjusted by the screw 24 to take up wear of the groove and key.

By providing the eccentric bore in the extension 5 12, the groove 20 can be made of the requisite depth without weakening the extension and so the dresser unit can be kept quite compact. If the extension were bored centrally for the piston-rod 15, the extension would have to be of considerably larger diameter to permit cutting a key-way in it and thus the size of the whole unit would be increased.

In Figure 1, 25 designates a diamond dressing tool such as is commonly used in dressing mechanism. The tool is mounted for rotatable adjustment in a lug 24 formed integral with a plate 26 and the plate 26 is fastened by screws 27 to the head of the skirt 18. The diamond 25 projects at one side from this plate 26 in position to dress the side of a grinding wheel on reciprocation of the piston 14.

In Figure 2, one of the dressing units is shown arranged to carry both a side dresser and a tip dresser. The side dresser is again designated as 25, while 28 denotes the tip dresser. The plate 29 which carries the two dressers 25 and 28 is of a different shape from the plate 26 which is intended to carry the single dresser. The plate 29 is provided with an arm 30 that extends a considerable distance forward from the plate. The side and tip dressers are both mounted in this arm. The side dresser 25 is rotatably mounted in the forward end of the arm in a manner similar to its mounting upon the plate 26.

The tip dresser 28 is here shown as having a conical operating surface and as being threaded into the arm 30 for adjustment thereon axially of its conical operating surface. To permit precise adjustment of this tip dresser 28, it may be adjusted against a stop-screw 31 that is threaded into an arm 32 also formed integral with the plate 29.

The tip dresser 28 may be made of carboloy or a similar material embedded with small diamonds 45 or it may be made of some hard material like carborundum. The operation of the tip dresser will be described more particularly hereinafter.

The dressing units are hydraulically operated. We shall first describe the operation of the embodiment shown in Figure 1. Here the operation of the dresser unit is controlled by a reverse valve 35. This valve 35 is mounted to slide in a sleeve 36 that is secured in a valve-casing 37.

The valve 35 is provided with spaced peripheral grooves 38, 39, 40, 41 and 42. The sleeve 36 is likewise provided with spaced peripheral grooves 44, 45, 46, 47 and 48. Each of the grooves 44, 45, 46, 47 and 48 is connected with the bore of the sleeve by a series of radial ducts that are drilled from the interior of the sleeve into the grooves. The ducts that connect the groove 44 with the interior of the sleeve 36 are designated at 50, the corresponding ducts which cooperate with the groove 45 are denoted at 51, while 52, 53 and 54, respectively, denote the ducts leading from the grooves 46, 47 and 48, respectively.

The valve stem 35 is provided with a central bore or duct 55. This communicates with the groove 39 through radial ducts 56 and with the groove 41 through radial ducts 57. One end of the bore 55 is formed with a tapered-seat for a tapered throttle valve 58 and near its other end, the bore is formed with a seat for a ball-relief valve 61 which is pressed to closed position by the spring 61'.

The valve stem 35 is also provided with a bore 59 which is in alignment with the bore 55. When the throttle valve 58 is open, fluid can flow from the duct 55 through the throttle valve opening into the bore 59 and thence through radial ducts 60 into the groove 42 in the valve stem.

The throttle valve 58 is integral with a rod 62 that is threaded for a portion of its length to thread adjustably into the bore 59. The rod 62 carries a pin 63 at its rear end that engages in a longitudinal slot 64 formed in the valve-cap 65 to hold the rod 62 against rotation relative to the valve-casing 37. By rotating the valve stem 35, then, the amount of opening of the throttle valve 58 can be adjusted to control the rate of movement of the dressing diamond or diamonds across the face of the grinding wheel, as will hereinafter be further described. To insure accurate adjustment of the throttle valve, a graduated dial 65 is provided. This dial is secured to the valve stem 35 by a set-screw 66. The graduations of this dial read against a pointer 67 that is secured in any suitable manner to the valve-casing 37.

The reverse valve is operated by pushing or 25 pulling the knob 68 that is secured in any suitable manner to the valve stem 35. The groove 64 is long enough for the pin 63 to remain in engagement with it throughout the whole of the movement of the valve stem in either direction.

Spring-pressed detents are provided to hold the valve stem at either limit of its reciprocating movement. These may take the form of balls 70. The valve stem is provided at its inner end with an enlarged head 71. This head is beveled off as 35 indicated at 72 and is provided with a V-shaped groove as indicated at 73. The sleeve 36 is provided at its inner end with an enlarged head 75 that engages a shoulder formed interiorly of the valve casing 37 to hold the sleeve against axial movement in one direction in the casing. The end of this head 75 is beveled off as indicated at 76. The balls 70 are mounted in holes drilled in the valve-casing and are pressed interiorly of the casing by the coil springs 78 which are interposed between the balls and the plugs 79 which thread into the casing. The spring-pressed balls will ride on the sides of the groove 73 and the side of the bevel 72 and hold the valve stem resiliently in either limit of its movement.

The valve casing 37 is connected with an oil pump or other suitable sort of fluid supply by the pipe 80. The pipe 81 is an exhaust line leading from the valve casing back to a sump. The valve casing is connected with the cylinder 55 11 by flexible piping 82 and 83. The piping 83 threads at one end into a cap plate 84 that closes the outer end of the cylinder 11 and is secured to the support 10 by screws 85. At its other end, the piping 82 threads into the valve casing 37 and communicates with the groove 47 of the sleeve 36. The piping 82 also threads at one end into the cap-plate 84. It communicates with a duct 86 (Figures 1 and 7) and also with a duct 87 that leads into a duct 88 that extends parallel to the duct 86. A duct 89 leads from the duct 86 into the cylinder 11 at a point intermediate the ends of the cylinder. A duct 91 leads from the duct 88 into the cylinder 11 at 70 the forward end of the cylinder. The ducts 86, 87, 88, 90 and 91 are drilled into the support 10. The outer ends of the ducts 90 and 91 are closed by plugs 92 and 93, respectively. At its other end, the piping 82 threads into the casing 37.

at a point to communicate with the groove 45 of the sleeve 36.

A ball-check valve 95 is provided in the duct 86 to prevent flow of fluid through said duct 5 in one direction. The ball-check valve is normally held in operative position by the coil-spring 96.

In the position of the parts shown in Figure 1, the motive fluid flows from the supply line 80 through the groove 46 and ducts 52 in the sleeve 36, the groove 46 in the valve stem 35, the ducts 51 and the groove 45 of the sleeve 36, the piping 82, ducts 87, 88 and 91 into the forward end of the cylinder 11, forcing the piston 14 rearwardly in the cylinder to traverse the diamond 25 in one direction across the side surface of a grinding wheel. At this time, the fluid exhausts from the rear end of the piston 14 through the piping 83, the groove 47 and ducts 53 of the sleeve 36, the groove 41 and ducts 57 of the valve stem 35 into the duct 55 of this stem, forcing the throttle valve 58 open to the extent allowed by the adjustment of the rod 62, and flowing through the ports 60 of the valve stem, the groove 42 of the valve stem, the ducts 54 and groove 48 of the sleeve 36 into the line 81 whence the exhaust fluid returns to the sump.

When the knob 68 is pushed inwardly, the direction of travel of the diamond 25 is reversed. The motive fluid will then flow from the supply pipe 80 through the groove 46, ducts 52, groove 49, ducts 53, groove 47 and piping 83 into the rear end of the cylinder 11, forcing the piston 14 forward in the cylinder. At this time, the fluid exhausts from the cylinder 11 through the ducts 90 and 91, 86, 88 and 87, the line 82, groove 45, ducts 51, groove 39, ducts 56 into the duct 55. The pressure of the liquid will force the relief valve 61 open and the liquid will then flow through the throttle valve 58, ducts 60 and 54 and groove 48 into the exhaust line 81.

As the knob 68 is pushed inwardly, as described, the balls 79 roll up out of the groove 73 and drop behind the bevel 72, holding the valve stem in its rearward position. With the construction shown in Figure 1, to reverse the valve again, it is necessary to pull the valve stem outwardly by grasping the knob 68 and pulling thereon. This will cause the balls 79 to ride up the bevel 72 and drop back into engagement with the groove 73.

It will be noted from the preceding description that the relief valve 61 operates in only one direction of movement of the piston 14. The purpose of providing this relief valve is to make the pressure on one side of the piston when it is moving in one direction equal that on the opposite side of the piston when it is moving in the opposite direction so that the dressing diamond will move across the grinding wheel at the same rate in either direction of its movement. The effective area of the piston is less on its front side than on its rear side because the piston rod 15 is secured to the front side of the piston. The relief valve 61 acts, however, to resist forward movement of the piston. By using a spring 61' of the proper tension, enough resistance can be built up against the forward movement of the piston so that despite the greater effective area of the rear side of the piston, the piston will not move forward in the cylinder by pressure on its rear face faster than it will move rearwardly by pressure on its front face. If a difference in rate of movement of the

diamond in opposite directions is of no moment, the relief valve 61 can be omitted.

The ball-check valve 95 has no special function when a single dresser unit is employed and it is ordinarily preferred to omit it in a single dresser unit. Its purpose will appear herein-after in the explanation of the operation of the dressing mechanism when a pair of dressing units are combined together.

It is a difficult but a very necessary task to protect a dressing unit against grit and water, for if grit or water get into the unit it will quickly wear out or rust. Telescoping guards are provided to protect the dressing unit of the present invention, but guards have been used before and they are not always adequate protection against keeping grit and water from getting into the operating parts. Hence, we have provided a very simple and inexpensive device for the maintaining the parts free of grit or water.

The telescoping guards are clearly shown in Figure 1. There is a tubular guard 109 secured in any suitable manner to the sleeve or skirt 18 and there are two tubular guards 101 and 102 secured in any suitable manner to the support 10. The guards 101 and 102 are of such diameter and so spaced from one another that the guard 100 will telescope between them and the guard 101 is also of such diameter that it will surround the skirt 18. Felt rings 104 may be inserted in the skirt 18 to further help seal and protect the piston rod 15 and guide 12. As a still further protection, a breather valve is mounted in the support 10. This valve comprises the sleeve 105 (Figures 1 and 6), seat 106 and disc 107. The sleeve 105 threads into a hole in the support 10 and serves to hold the seat 106 against a shoulder on the support 10. The seat 106 has a recess 108 in its bottom face and the disc 107 fits into this recess. The depth of the recess 108 is sufficient to permit the disc 107 to move freely up and down in the recess.

The sleeve 105 is hollow and communicates with the outer air through the opening 109. The seat 106 has a central opening 110 extending therethrough and the disc 107 is also provided with a central aperture 111 but of much smaller diameter than the opening 110 in the seat 106.

Two ducts 112 and 113 are formed in the casting 10 and lead from the seat 106 at diametrically opposed points. These ducts communicate with a duct 114 that extends into the pocket formed between the guard 101 and guide 12 and in which the skirt 18 moves.

The bore of the sleeve 105 is filled with steel wool or any other suitable material for straining dirt from the air which may be drawn in through the breather valve.

When the piston 14 moves to the right in the cylinder 11, air is drawn from the outside through the opening 109, the bore of the sleeve 105, the duct 110 in the valve seat 106 and around the disc 107 into the ducts 112 and 113 and thence into the pocket between the guard 101 and the cylindrical guide or support 12. When the valve stem 35 is reversed and the piston 14 moves to the left, the disc 107 is forced against the seat 106 and the air previously entrapped can only escape through the very small opening 111 in the disc 107. It is therefore forced forwardly between the guard 101 and the skirt 18 and thence between the guard 101 and the guard 100 and thence between the guard 100 and the guard 102. Air is thus blown through this circuitous passage 75

and any dirt or grit or water that might have gotten between the guards as they extended is blown out as they telescope again.

In most cases, it is desirable to leave a small opening 111 in the disc 107 to prevent building up of excessive pressure when the guards telescope together, but, if desired, the opening 111 might be omitted entirely.

Packing 115 is provided to prevent leakage of oil from the cylinder 11 along the piston rod 15, while packing 116 is provided to prevent leakage of oil along the rod 62. The nut 117 which threads into the head 71 of the valve stem 35 serves to hold this latter packing in position. Oil leaking outwardly along the valve stem is returned to the sump through the ducts 50, groove 44 and leak-return pipe 118.

Where it is desired to dress two sides of a grinding wheel as required, for instance, in the case of wheels for grinding gear teeth, two of the dresser units may be coupled together and controlled by a single reverse valve and a single throttle valve. One method of so coupling two dressing units together is illustrated in Figure 1, where I have shown a second dressing unit coupled in circuit with the unit already described in such manner that the two dresser diamonds move simultaneously in opposite directions. The second dresser unit is shown in dotted lines. The two dresser units shown are absolutely identical in construction, but for the purpose of more readily describing their operation, I have designated parts of the second unit by primed reference numerals.

To operate the two dresser units, the line 82 is extended, as shown in dotted lines at 82', into the rear of the cylinder 11' instead of connecting with the duct 86 drilled in the casing 10. The two ducts 88 and 88' require also to be connected as by the dotted pipe line 120.

When the valve stem 35 is in the position shown in Figure 1, the pressure fluid will flow from the pipe line 82—82' into the cylinder 11' forcing the piston 14' forward and moving the diamond 25' to the right. The fluid exhausting from the front end of the piston 14' flows through the ducts 88' and 88 into the line 120 whence it flows through the ducts 86, 88, 90 and 91 into the front end of the cylinder 11, forcing the piston 14 rearwardly in this cylinder and moving the diamond 25 to the left. The exhaust fluid flowing from the rear end of the cylinder 11 passes through the line 83 to the valve casing 31, whence it returns to the sump. When the valve stem 35 is shifted, by pushing in the knob 68, the pressure fluid flows through the line 83 into the rear of the cylinder 11, moving the piston 14 and dresser 25 to the right. This forces the fluid out of the front end of the cylinder 11 through the ducts 90 and 91, 86 and 88 into the line 120 whence it is carried through the ducts 88' and 91' (the valve 95' being forced shut) into the front end of the cylinder 11'. Thus the piston 14' is forced rearwardly in the cylinder 11' and the diamond 25' is carried to the left. The fluid in the rear of the piston 14' at this time exhausts through the line 82—82'. Thus with the piping arranged as described, the single reverse valve controls the two dresser units and the two dressers move simultaneously in opposite directions.

When a single dresser unit is used, the motive fluid will flow from the source of fluid supply alternately to the front and rear ends of the piston 14. Thus the two chambers formed in

the cylinder 11 on the opposite sides of the piston 14 are alternately filled with oil from the source of fluid supply. When two dresser units are used, however, and coupled together in the manner shown in Figure 1, the front ends of the two pistons 14 and 14' are not connected directly to the source of fluid supply. If no ball-check valves 95 and 95' were used, no pressure fluid would ever get into the front ends of the pistons 14 and 14', save that which would leak by these pistons in their movements, and the two pistons in their forward movements would simply be compressing what air was entrapped between the pistons and the forward end walls of the cylinders 11 and 11', respectively. The air entrapped in the forward ends of the two cylinders or the oil that would leak past the two pistons into the forward ends of the two cylinders, would never operate the two dressing units with precision. The pistons probably would not move fully to the left on their return strokes and where it was possible for varying amounts of fluid to leak past the pistons, the strokes of the pistons would vary in length depending upon the amount of leakage.

To insure uniform and full strokes of the two pistons at all times, the ball check valves and ducts 86—90 and 86'—90' are provided. The first time the mechanism is operated, the air in the front end of the cylinder 11' may be compressed, but the pressure fluid will force the piston 14' 30 far enough forward in the cylinder 11' to clear the duct 90' and then the pressure fluid will flow through the ducts 90' and 86', forcing the ball check valve 95' open and flowing through the line 120 and ducts 87, 88 and 91 into the front 35 end of the cylinder 11. Thus the piston 14 will be forced rearwardly in the cylinder 11, not by air compressed in the front end of the cylinder 11', but by pressure fluid delivered directly from the pump through the ducts 90' and 86' and the 40 ball check valve 95'.

Similarly, when the valve stem 35 is reversed, the piston 14 will be forced forward in the cylinder 11 far enough to clear the duct 90 and the pressure fluid will then flow through that duct 45 and the duct 86, opening the ball check valve 95 and flowing through the line 120 and ducts 88' and 91' into the front end of the cylinder 11'.

Thus, by use of the two ball check valves in conjunction with ducts 90 and 90', which enter the two cylinders at points intermediate to the ends of the two cylinders, assurance can be had that the motive fluid will flow to both sides of the pistons 14 and 14' and that these pistons will be operated uniformly. Of course, to insure this uniform operation, it is desirable to eliminate any air entering the system. This can be done by simply opening the plugs 92 and 93, 92' and 93' slightly and operating the pistons a few times until the air is forced out of the pistons and oil begins to seep out the plugs. Then when the plugs are tightened, the system will be free of air.

With a reverse valve built and operated as described with reference to Figure 1, the operator of the machine must push the knob 68 in to move the diamonds in one direction and pull the knob out again to move the diamonds in the opposite direction. This is an improvement over manually operated dressers, as heretofore constructed, for previous dressers have required that the operator actually move the diamonds across the grinding wheel. Where the wheel can be dressed by a single passage of the diamond across its face and where the diamond can be moved far enough in this passage to clear the wheel, the construction 75

of Figure 1 can be used advantageously, but where the diamond must be passed twice across the wheel to complete the dressing or must be returned to initial position to clear the wheel, the construction of Figure 1 has its limitations, so far as efficiency is concerned, because the operator is required to manipulate the reverse valve twice to complete the dressing cycle.

Where an operator is attending a number of machines, a considerable gain can be achieved if provision is made whereby, once the dresser is put into operation, it will complete its cycle of operation automatically. Such an improvement in construction constitutes one of the principal features of the present invention and will now be described.

The reverse valve stem 35 shown in Figure 2 and the sleeve in which it slides are of identical construction with the valve stem and sleeve shown in Figure 1, except that there are a pair of pins 125 (Figures 2 and 8) mounted in the head 71 of the valve stem, one at either side of the rod 62. The valve and sleeve are simply shown in elevation in Figure 2, whereas they are shown in section in Figure 1. These two pins 125 pass through openings in the head 65 and engage, respectively, the furcated ends of a lever 126 that is pivoted at 127 in a cap 128 that is secured to the casing 130 in which the valve is housed.

The casing 130 is not only bored to receive the sleeve 35, but it is provided with a parallel bore forming a cylinder 132 and with a bore 133 that communicates with the cylinder 132.

There is a piston 135 mounted to reciprocate in the cylinder 132. This piston is formed with an integral rod or stem 136, that is hollow, and is adapted to extend into the bore 133. There is a plunger 137 mounted to reciprocate in the bore 133. This plunger telescopes at one end into the bore of the piston rod 136 and engages at its other end the arm 139 of the lever 126. A coiled spring 140 that is mounted in the bore of the piston rod 136 serves to urge the plunger 137 in a direction outward of the bore of this piston rod. There is a disc 138 carried by this plunger, the purpose of which will appear hereinafter.

One end of the cylinder 132 is closed by the plate 142 which is secured in any suitable manner to the casing 130. To prevent leakage of oil along the piston rod 136 through the other end of the cylinder, a packing 143 is provided.

The pressure fluid is pumped to the casing through the pipe 145 which takes the place of the pipe 80 of Figure 1 and is connected to the casing 130 at a point corresponding to that at which the pipe 80 enters the casing 37 of Figure 1. The exhaust fluid flows from the casing 130 through the pipe 146 which corresponds to the pipe 81 of Figure 1 and is connected to the casing 130 at a corresponding position. The duct 147 communicates with the sleeve 35 at the same point that the pipe 83 communicates with the sleeve 35 in Figure 1. This duct 147 is connected with the piping 148. At a point corresponding to where the pipe 82 enters the casing 37 of Figure 1, there is a duct 150 in the casing 130 of Figure 2. This duct communicates with the cylinder 132 through the ducts 151 and 152 and the port 153 drilled in the casing 130. There is a line 155 leading from one of the dresser units to the other end of this cylinder 132. The two dresser units are also connected by a line 156.

When the parts are in the position shown in Figure 2, the duct 150 will be on supply from the line 145 because of the position of the reverse

valve 35. The pressure fluid will flow through the ducts 150, 151 and 152 and the port 153 forcing the piston 135 to the left in the cylinder 132 as shown. Oil in the left end of the cylinder 132 will be forced out of the cylinder through the line 155 into the cylinder 11', forcing the piston 14' forward in this latter cylinder and carrying the diamond 25' across the outer side surface 160 of the grinding wheel W. The movement of the piston 14' forward in the cylinder 11', will force the fluid in the cylinder 11' in front of the piston 14' out through the ducts 91' and 93', 88' and 86' and the check valve 95' into the line 156, whence it passes through the ducts 88 and 91 into the front end of the cylinder 11. Hence the piston 14 is moved rearwardly in the cylinder 11 and the dresser 25 is moved backwardly across the inside surface 161 of the grinding wheel W. The movement of the piston 14 rearward in the cylinder 11 forces the fluid behind the piston out through the line 148 and duct 147 into the valve casing whence it returns through the throttle valve 58, as described with reference to Figure 1, and pipe 146 to the sump.

When the operator pushes the knob 68 inwardly, the direction of application of fluid pressure through the pistons 14 and 14' will be reversed, as described with reference to Figure 1. Also when the valve stem 35 is pushed inwardly, the pins 125 will rock the lever 126 about its pivot pin 127 against the resistance of the spring 140. The plunger 137 will, therefore, be pushed into the bore of the piston rod 136 and the spring 140 will be compressed. The plunger 137 will be resiliently held in this last described position because when the valve stem 35 is pushed inwardly, the detents 70 will ride up out of the groove 73 and drop behind the bevel 72 of the head of the valve stem.

Having pushed the valve stem in, the operator can go away and leave the dressing mechanism and it will perform its cycle without his further attention. When the valve stem is pushed inwardly, as described, line 148 will be put on supply. The piston 14 will move forwardly in its cylinder 11, moving the diamond 25 forwardly across the inside surface 161 of the grinding wheel W. The fluid in the forward side of the piston 14 will be forced out of the cylinder 11 through the ducts 90, 91, 86 and 88, into the line 156 and thence through the ducts 88' and 91' into the front ends of the cylinder 11'. This will move the piston 14' rearwardly in its cylinder drawing the diamond 25' rearwardly across the side face 160 of the grinding wheel. The fluid forced out of the rear end of the cylinder 11' in this movement will flow through the pipe 155 into the cylinder 132. This will force the piston 135 to the right in this cylinder, further compressing the spring 140 which, as already described, is already compressed somewhat because at this time the plunger 137 is being held over to the left from the position shown in Figure 2 by the lever 126.

As the piston 135 continues to move to the right, the spring 140 will be compressed still further until the right end of the piston rod 136 strikes the disc 138 carried by the plunger 137. Then the plunger 137 will be moved on to the right with the piston 135. This will rock the lever 126 about its pivot 127 back to the position shown in Figure 2. The ball detents 70 will ride up the bevel 72 and the reversing valve will be returned to the position shown in Figure 2. As soon as the ball detents have cleared the bevel 75

72 and are riding on the flat 162 between the bevel 72 and the groove 73, the spring 140 will come into action and push the reverse valve quickly on back to the leftward position shown 5 in Figure 2.

The return of the reverse valve to the position shown in Figure 2 will put the duct 150 again on supply and the line 148 again on exhaust. The pressure fluid entering the cylinder 132 10 through the port 153 will force the piston 135 back to the left to the position shown in Figure 2. The fluid forced out of the left end of the cylinder 132 by this leftward movement of the piston 135 will flow through the line 155 into the cylinder 11' and the diamond 25' will be moved 15 forward across the grinding wheel to return to the position shown in Figure 2 and moved far enough forward to clear the wheel. The fluid forced out of the front end of the cylinder 11' 20 in this movement will flow through the line 156 into the front end of the cylinder 11. The diamond 25 will be drawn back across the grinding wheel and returned to the position shown in Figure 2. The fluid forced out of the rear end of 25 the cylinder 11 in this movement will pass through the reverse valve and the throttle valve into the exhaust line 146.

The dressing mechanism will now have completed its cycle. As indicated, all that it is necessary for the operator to do is to push the reverse valve inwardly and the two diamonds will be passed back and forth across the two sides of the grinding wheel and the parts returned to initial position without any further attention on 35 his part. For fine work, the throttle valve 58 will be adjusted to allow only a very slow exhaust in order to obtain a very slow travel of the diamonds across the face of the grinding wheel. But the slowness of their movement does not 40 interfere with the work of the operator. He can attend to other duties. Even if he has only one machine to operate, the use of the dressing mechanism disclosed in Figure 2 will render him more efficient for during the dressing interval, 45 he can remove a completed work piece and chuck a new blank in place on the grinding machine.

Where only the sides of a grinding wheel are to be dressed, the diamonds need only be moved across the grinding wheel in one direction far 50 enough to dress the side for the full length and may then be returned to initial position. When it is desired to dress the tip of the grinding wheel also and the tip dressing tool is mounted on the same support with one of the side truing tools, 55 as is the tool 28 of Figure 2, then a dwell must occur at the end of the forward stroke of the piston 14 and this dwell must be of sufficient duration to permit the tip of the wheel to be dressed.

To secure this dwell, the cylinder 132 is made 60 longer than the cylinders 11 or 11' if the three cylinders are of the same diameter. Thus, after the pistons 14 and 14' have bottomed in their respective cylinders at the ends of their strokes, the piston 135 will still have to travel some distance before the piston rod 136 engages the disc 133 and trips the reverse valve. The distance of 65 this overtravel of the piston 135 determines the length of the dwell of the tip-dresser 28 in engagement with the grinding wheel.

70 Where the piston 135 has this overtravel, a greater volume of fluid is required to move the piston to either end of the cylinder 132 than can be contained in either the cylinder 11 or 11'. To insure that the piston 135 be moved in both 75 directions to the full extent of the stroke, a sec-

ond ball-check valve and overflow duct must be incorporated in each truing unit.

For this purpose, the top-plates 165 and 165' 5 of the two dressing units shown in Figure 2 should be drilled to provide ducts 166 and 166', respectively. The casings 10 and 10' should also be drilled to provide ducts 167 and 167', respectively, and ducts 168 and 168', respectively, which communicate therewith and which lead into the cylinders 11 and 11', respectively, at points removed from the rear ends of said cylinders at 10 distances greater than the thickness of the pistons 14 and 14'. Ball check valves 169 and 169' operate in the ducts 167 and 167', respectively, and are normally held closed by springs 170 and 15 170'.

With this modified construction, when the piston 14' has bottomed in the rear end of the cylinder 11', the pressure fluid flowing into the front end of this cylinder will continue through 20 the duct 168', ball-check valve 169' and ducts 167' and 166' into the line 155, driving the piston 135 on to the limit of its movement to the right in the cylinder 132.

When the piston 135 moves back to the left to 25 the position shown in Figure 2, the fluid in the cylinder 132 on the left-hand side of the piston 135 is forced out of the cylinder. Since the cylinder 132 has a greater capacity in volume than the cylinders 11 and 11', the excess fluid must be 30 taken care of. The valve 169 in the dresser unit 10 does this. The fluid that is flowing out of the left end of the cylinder 132 passes through the line 155, forcing the piston 14' forward in the cylinder 11'. After the piston 14' has bottomed 35 in the cylinder 11', the excess fluid flows through the ducts 90' and 91' and connecting ducts into the line 156 and thence through the duct 88 and duct 90 into the cylinder 11, forcing the piston 14 rearwardly in this cylinder. After the 40 piston 14 has bottomed in the rear end of the cylinder 11, the excess fluid will pass off through the duct 168, valve 169 and ducts 167 and 166 into the line 148, whence it will return through 45 the reverse and throttle valves to the sump.

When the dressing mechanism is arranged to provide a dwell at the end of the stroke of the side-trimming diamond as described, the diamond 25 will be carried across the side 161 of the wheel W and when the piston 14 has bottomed 50 in the forward end of the cylinder 11, the tip-trimming tool 28 will engage the tip surface 170 of the wheel. The tip-trimming tool 28 will remain in engagement with the wheel until the piston 135 has moved fully over to the right and 55 tripped the reverse valve. Thus, depending upon the dimensions of the cylinder 132, the tip-trimming tool 28 can be caused to remain in engagement with the tip of the grinding wheel for more or less time, as may be required, to true the tip 60 surface of the wheel satisfactorily.

Preferably, the diamond 25 and truing tool 28 will be spaced far enough apart to allow the diamond 25 to clear the side 161 of the wheel before the truing tool 28 actually engages the tip surface 170 of the wheel.

The tip-truing tool 28 may be made of any 70 desired shape. If the tip surface 161 of the wheel is to be inclined at other than a right angle to the axis 172 of the grinding wheel, a conical truing tool such as shown as 28 is preferred. When the tip surface of the wheel is perpendicular to its axis, a cylindrical tip truing tool might be substituted for the conical tool 28 and used directly in place of the tool 28. As stated, how- 75

ever, the shape of the tip truing tool may be chosen at will to serve the purpose for which it is intended.

In Figures 1 and 2, the dressers are shown coupled together to move simultaneously in opposite directions. Figure 3 shows diagrammatically how they might be coupled together to move simultaneously in the same direction. The same reference numerals heretofore used are employed in Figure 3 to designate like parts.

When the pressure fluid is flowing through the line 175, the piston 14' is forced to the rear in the cylinder 11' and the fluid in the rear end of this cylinder is forced out through the line 176 into the forward end of the cylinder 11. This forces the piston 14 also rearwardly in its cylinder 11. The fluid forced out of the rear end of the cylinder 11 passes through the line 177 into the rear end of the cylinder 132, forcing the piston 135 to the right to trip the reverse valve. As soon as the reverse valve is shifted, the pressure fluid will flow through the line 177, forcing the piston 14 forward in the cylinder 11 and driving the fluid in the forward end of this cylinder through the line 178 into the rear end of the cylinder 11'. The fluid in the forward end of this cylinder is then forced through the line 175, the reverse and throttle valves into the line leading back to the sump.

The diamonds 25 and 25' move forward together and rearwardly together when the units and the reverse valve are coupled as shown in Figure 3. The only change required to achieve this result is a change in the coupling of the connecting pipe lines.

In Figure 3, only one set of ball-check valves has been shown for the sake of clearness, but it will be understood that if it is desired to obtain a dwell of the trip-trimming tool 28 in engagement with the grinding wheel, then a second set of ball-check valves should be provided to operate in exactly the same manner as the second set used in the mechanism of Figure 2.

When two dresser units are coupled together as suggested in Figure 1, the relief valve 61 in the exhaust duct 55 of the valve-stem 35 is not required. The front ends of the two pistons 14 and 14' are connected together and the difference in pressure on the front and rear faces of each piston is the same whether the piston be moving to the right or the left. Hence each diamond will be moved at the same rate in one direction as in the other. Where a pair of dresser units are connected, however, with a third piston, as the piston 135 of Figure 2, which itself has different effective areas on its two faces, the relief valve 61 is required if the two diamonds are to move at the same rates in opposite directions. The difference in area between the front and rear faces of the piston 135 constitutes an unbalanced condition which must be offset by the action of the relief valve 61.

No particular mounting for the truing units and the reverse valve has been shown in any of the drawings, but it will be understood that they may be mounted in any suitable way and at any convenient location upon the grinding machine with which the truing units are to be used. It will be further understood that, while the diamonds 25 and 25', have been referred to as side-trimming tools, one or other of them might, if desired, be used to dress the tip of a grinding wheel by a reciprocating movement across the tip surface of the rotating wheel, in case it was not desired to use a tip-trimming tool similar to

that shown at 28. It will be obvious, also, that instead of using two dressing units, one of which carries both a side and a tip-trimming tool, that three dressing units might be coupled together, where it is desired to use a reciprocating trimming tool for the tip as well as the side surfaces of a wheel. The three units could be operated from one reverse and one throttle valve and might be identical in construction.

Certain features of the invention will have wide applications and are not limited to use in dressing mechanisms. In general it may be said that the present application is intended to cover any adaptations, uses, or embodiments of the invention, following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described our invention, what we claim is:

1. In a dressing mechanism for a grinding wheel, a reciprocable member, a dressing tool mounted on said member for dressing a side surface of the wheel, a dressing tool mounted on said member for dressing the tip surface of said wheel, said dressing tools being spaced from one another to allow the side dresser to complete its stroke before the tip dresser engages the wheel, and means for actuating said reciprocable member to cause it to move alternately in opposite directions with a dwell at the end of its stroke in one direction when the tip dresser is in engagement with the wheel.

2. In a dressing mechanism for grinding wheels, a reciprocable member, a dressing tool mounted on said member for dressing a side surface of the wheel, a dressing tool mounted on said member for dressing the tip surface of the wheel, said tip dresser being spaced from said side dresser far enough to allow the side dresser to complete its stroke before the tip dresser engages the wheel, means movable in opposite directions for moving the reciprocable member correspondingly in opposite directions, said last named means being manually operable in one direction to bring the two dressing tools successively into engagement with the grinding wheel, and means for automatically moving said means in the opposite direction after a dwell of the tip dressing tool in engagement with the wheel.

3. In combination, a support having a longitudinal bore formed eccentrically therein and having a longitudinal groove formed in its periphery at the point most remote from the center of said bore, a member shaped to fit said bore and reciprocable therein, a projecting member secured to said reciprocable member, and means carried by said projecting member adapted to engage in the groove of said support to guide said reciprocable member in its movements in the bore of said support.

4. In combination, a support of cylindrical shape having a cylindrical bore formed eccentrically therein and having a longitudinal groove formed in its periphery at the point most remote from the center of said bore, a cylindrical member reciprocable in said bore and having a sleeve secured thereto to surround said support, and a tongue carried by said sleeve adapted to engage in the peripheral groove of said support to guide said reciprocable member in its movements.

5. In combination, a support having a cylinder formed therein and having a cylindrical guide projecting from one end of said cylinder, said guide having a longitudinal cylindrical bore formed therein eccentrically of the periphery of said guide and having a longitudinal groove formed in its periphery at the point most remote from the center of said bore, a piston reciprocable in said cylinder, a piston-rod secured to said piston and projecting from said cylinder through the bore of said guide, a sleeve secured to the outer end of said piston-rod to surround said guide, a tongue secured to the interior of said sleeve adapted to engage in a groove of said guide, a dressing tool secured to said piston-rod, and means for admitting fluid pressure alternately to opposite sides of said piston to reciprocate said dressing tool.
6. In combination, a pair of cylinders and a piston reciprocable in each cylinder, a reverse valve controlling the direction of application of fluid pressure to said pistons, a duct connecting the reverse valve with one end of one cylinder, a duct connecting the other end of said cylinder with one end of the other cylinder, means for moving the reverse valve manually in one direction, means for moving the reverse valve in the opposite direction, and a duct connecting the second end of the second cylinder with the last named means to apply fluid pressure to the last named means to operate the same on movement of the piston in one direction in the second cylinder.
7. In combination, a support, a tubular member having one end closed and adapted to slide telescopically on said support, a guard secured to said support and surrounding said tubular member, a valve carried by said support connecting with the outside air and adapted to be opened when the tubular member is moved outwardly on said support to admit air between the relatively telescoping members and adapted to be closed on reverse movement of said members, and means for reciprocating the tubular member on said support.
8. In combination, a cylinder and a piston reciprocable therein, a reverse valve having a longitudinal bore therein, supply and exhaust ducts leading to said valve, one of which connects with said bore, a throttle valve controlling the flow of fluid from said bore to the duct that connects therewith, a stop member limiting the opening of said throttle valve and having a threaded connection with said reverse valve, means for holding the last named member against rotation, means connecting the reverse valve with opposite ends of said cylinder, said reverse valve being reciprocable to apply fluid pressure alternately to opposite ends of said piston, and said reverse valve being also rotatable to adjust said stop member.
9. In combination, a cylinder and a piston reciprocable therein, a reverse valve for controlling the direction of application of fluid pressure to said piston, a second cylinder and a second piston reciprocable therein, means for moving the reverse valve in one direction, means operable by the second piston, after a predetermined movement in its cylinder, for moving the reverse valve in the opposite direction, and means whereby movement of the first piston in one direction in its cylinder operates to move the second piston in the last described direction in its cylinder.
10. In combination, a cylinder and a piston reciprocable therein, a reciprocable reverse valve for controlling the direction of application of fluid pressure to said piston, a second cylinder and a second piston reciprocable therein, a plunger mounted in alignment with the second piston and spaced therefrom to be positively movable thereby after a predetermined movement of the second piston in one direction, a duct connecting one end of the first piston to the reverse valve, a second duct connecting the other end of the first piston to one end of the second piston to move said second piston into engagement with the plunger on movement of the first piston in one direction in its cylinder, a duct connecting the opposite side of the second piston with the reverse valve, said reverse valve in its movement connecting the first and third ducts alternately with fluid pressure supply and exhaust, means operatively connecting the reverse valve and plunger to move one on movement of the other, means for resiliently holding the reverse valve at either limit of its movement, said last named means being disengageable in one direction on positive movement of the plunger and a coil spring interposed between the second piston and the plunger and adapted to be compressed on movement of the second piston into engagement with the plunger and operable to shift the reverse valve through movement of said plunger after the resilient holding means has been disengaged.
11. In combination, a cylinder and a piston reciprocable therein, a reciprocable valve for controlling the direction of application of fluid pressure to said piston, a second cylinder and a second piston reciprocable therein, a plunger mounted in alignment with the second piston and spaced therefrom to be positively movable thereby after predetermined movement of the second piston in one direction, a duct connecting one end of the first piston to the reverse valve, a second duct connecting the other end of the first piston to one end of the second piston to move the second piston into engagement with the plunger on movement of the first piston in one direction in its cylinder, a duct connecting the opposite side of the second piston with the reverse valve, auxiliary ducts connecting each of the first ducts with the first cylinder at points intermediate the length of said cylinder, a check valve cooperating with each of the auxiliary ducts to close the same against flow of fluid therethrough into said cylinder but permitting flow of fluid from said cylinder, a pivoted lever operatively connected at one end to the reverse valve and on its opposite end to said plunger, said reverse valve in its movement connecting the first and third ducts alternately with supply and exhaust lines, means for resiliently holding the reverse valve at either limit of its movement, said means being disengageable in one direction on positive movement of the lever by engagement of said piston with said plunger, and a coiled spring interposed between the second piston and plunger and adapted to be compressed on movement of the second piston into engagement with the plunger to shift the reverse valve after the resilient holding means has been disengaged by movement of said lever.
12. In combination, a cylinder and a piston movable therein, a reverse valve controlling the movement of said piston, a second cylinder and a second piston movable therein, a single hydraulic connection from one end of one cylinder to one end of the other cylinder, hydraulic connections between said reverse valve and the other ends of the two cylinders, the operation of said valve causing supply and exhaust of the motive

fluid alternately through the two last named hydraulic connections, means for moving said valve in one direction, and means whereby when the second piston has moved a predetermined distance in one direction in its cylinder, the reverse valve is reversed.

13. In combination, a cylinder, a piston reciprocable therein and having a piston rod projecting from one face thereof, a valve casing, a duct connecting the described face of piston with said casing, a second duct connecting the other face of the piston with said casing at a point spaced from the point of connection of the first duct therewith, supply and exhaust lines connected to said casing, a reverse valve reciprocable in the casing to connect the supply and exhaust lines alternately with said two ducts, and a spring-closed relief valve, and means whereby when the second duct is connected to supply, said relief valve is interposed between the first duct and the exhaust line so that exhaust from the first duct is against the resistance of the spring operating said relief valve.

14. In combination, a cylinder, a piston reciprocable therein, a reciprocable valve for controlling the application of fluid-pressure alternately to opposite ends of the piston, manually operable means for moving the valve in one direction to admit the pressure fluid to one end of the cylinder to move the piston in one direction, and means whereby the fluid flowing from the other end of said cylinder during said movement causes said valve to be reversed, after a predetermined dwell of the piston at the end of its movement in the first-mentioned direction, to reverse the movement of said piston.

15. In combination, a cylinder, a piston reciprocable therein, a reciprocable valve for controlling the application of fluid pressure alternately to opposite ends of the piston, a second cylinder, a piston reciprocable in said second cylinder, manually operable means for moving the valve in one direction, means connecting the second piston to said valve to move the valve in the reverse direction on movement of the second piston in one direction in its cylinder, and means connecting one end of the first piston with one end of the second piston to move the second piston in the described direction at the end of the movement of the first piston in its cylinder in the direction to which it is impelled on manual movement of the valve.

16. In combination, a cylinder, a piston reciprocable therein, a reciprocable valve for controlling the application of fluid pressure alternately to opposite ends of the piston, manually

operable means for moving said valve in one direction to admit the pressure fluid to one end of said cylinder to move the piston in one direction, a second cylinder into which fluid flows from the opposite end of the first named cylinder as the piston moves therein in the described direction, a piston reciprocable in the second cylinder, and means operatively connecting the second piston to said valve to reverse said valve after a predetermined dwell of the first piston at the end of its movement in the described direction.

17. In combination, a cylinder, a piston reciprocable therein, a reciprocable valve for controlling the application of fluid pressure alternately to opposite ends of the piston, manually operable means for moving the valve in one direction to admit the pressure fluid to one end of said cylinder to move the piston in one direction, a second cylinder and a second piston reciprocable therein, means operatively connecting the second piston to said valve so that one moves the other, said last named means operating to move the second piston in one direction in the second cylinder on the above manual movement of the valve, and means connecting the second cylinder with the end of the first cylinder which is on exhaust during movement of the first piston in the described direction, whereby to move the second piston in a direction to automatically reverse said valve.

18. In combination, a cylinder, a piston reciprocable therein, a reciprocable valve controlling the application of fluid pressure alternately to opposite ends of the piston, manually operable means for moving the valve in one direction to admit the pressure fluid to one end of said cylinder to move the piston in one direction, a second cylinder and a second piston reciprocable therein, means operatively connecting the second piston to said valve so that one moves the other, said last named means operating to move the second piston in one direction in its cylinder on the above described manual movement of the valve, the volumetric capacity of the second cylinder being greater than that of the first, means connecting the second cylinder with the end of the first cylinder which is on exhaust during movement of the first piston in the described direction, and means also connecting the pressure end of the first cylinder with the second cylinder after the first piston has bottomed in its cylinder on its first described movement, whereby to supply to the second cylinder the volume of the motive fluid required to automatically reverse said valve.
